[57] CLAIM

The ornamental design for a file box, as shown and described.

DESCRIPTION

FIG. 1 is a top, right front perspective view of a file box showing our new design;

FIG. 2 is a top plan view;

FIG. 3 is a front elevational view;

FIG. 4 is a right side elevational view, the left side being a mirror image thereof;

FIG. 5 is a rear elevational view;

FIG. 6 is a top, right front perspective view of a second embodiment of our new design; and,

FIG. 7 is a right side elevational view of FIG. 6, the left side being a mirror image thereof.

The FIG. 1 and FIG. 6 views have been drawn to a reduced scale with respect to FIGS. 2 through 5 and 7. The bottom plan views of the embodiments of FIG. 1 and FIG. 6 are plain and ornamented.
